UNITED STATES PATENT OFFICE

138,651

DESIGN FOR A URINE SPECIMEN APPARATUS

Dean H. Korotev and Jane M. Korotev,
Waukesha, Wis.

Application November 11, 1943, Serial No. 111,656

Term of patent 7 years

(Cl. D83—1)

To all whom it may concern:

Be it known that we, Dean H. Korotev and Jane M. Korotev, citizens of the United States and residents of Waukesha, in the county of Waukesha and State of Wisconsin, have invented a new, original, and ornamental Design for a Urine Specimen Apparatus, of which the following is a specification, reference being had to the accompanying drawing, forming part thereof.

Figure 1 is a side elevational view of a urine specimen apparatus showing my new design;
Figure 2 is a rear elevational view thereof;
Figure 3 is a top plan view thereof.

We claim:

The ornamental design for a urine specimen apparatus, as shown.

DEAN H. KOROTEV.
JANE M. KOROTEV.
